UNITED STATES PATENT OFFICE.

ALBERT BALL, OF CLAREMONT, NEW HAMPSHIRE, ASSIGNOR TO THE SUL-
LIVAN MACHINE COMPANY, OF SAME PLACE.

ROCK-BORING MACHINE.

SPECIFICATION forming part of Letters Patent No. 351,566, dated October 26, 1886.

Application filed December 2, 1885. Serial No. 184,440. (No model.)

To all whom it may concern:

Be it known that I, ALBERT BALL, of Clare-
mont, in the county of Sullivan and State of
New Hampshire, have invented a new and Im-
proved Rock-Boring Machine; and I do hereby
declare that the following is a full and exact de-
scription of the same, reference being had to
the accompanying drawings, and to the letters
of reference marked thereon.

10 My invention relates particularly to a drilling-machine for boring deep holes, and is es-
pecially used for underground prospecting in
connection with a diamond-armed head and
where it is convenient to have the drill mount-
ed on a light frame and not require much space
15 in its operation.

My object is to provide a drill which shall
be very light, require small room, be very eas-
ily worked, be very steady and very economi-
20 cal in its working, which can be at any angle
from horizontal to perpendicular. The use of
two parallel standards is not novel, nor is the
hanging upon such standards of a drilling-ma-
chine which can be turned in different direc-
25 tions; but one novelty of my invention con-
sists in the position and manner of setting my
machine upon such standards, between them,
so as to have the weight and strain directly
upon and against both standards, instead of
30 at one side of them, while at the same time the
drill can be swung on trunnions in a plane al-
most at right angles with the plane of the stand-
ards. These planes could be at right angles;
but I prefer to have them not quite rectangu-
35 lar, so as to allow of the engine-shaft not in-
terfering with the standards.

Other novelties of my invention consist in
the manner of securing my machine to the
standards; in the devices for swiveling the
40 drill without at the same time disturbing the
engine and its shaft; in the combination with
a special single-trunk engine; in the device
for raising and lowering the machine as neces-
sary in the process of drilling to remove and
45 change rods; and in the combination, with
these devices, of my improved friction-clutch
for feeding the drill and my device for rapid
adjustment of my machine for withdrawing
the rods.

The novelties in my machine-standards and 50
method of bracing the same are covered by an
independent application filed of even date here-
with.

For a better understanding of my improve-
ments in detail, attention is invited to the ac- 55
companying drawings, wherein—

Figure 1 shows my machine mounted on its
standards. Fig. 2 is a top view of the same.
Fig. 3 is an enlarged sectional view of part of
the machine, including the feed mechanism. 60
Fig. 4 is an end view of the same; and Fig. 5
is a top view of the same, with some of the
parts removed, showing the mechanism for
swiveling the machine and for clamping it to
the standards. 65

Similar letters of reference indicate corre-
sponding parts.

A A represent the standards whereon the
machine generally is supported when in use,
although for some work other supports could 70
be used.

B B, Figs. 1 and 2, are the "stretchers"
which stiffen the standards and keep them
parallel.

C C² C³ C⁴, Figs. 1, 2, and 5, are clamps 75
which hold the machine to the standards.

D D, Figs. 1 and 2, are the "brace-clamps."
j, Figs. 1 and 2, is one of the "braces." For
a detailed description of these braces and brace-
clamps I would refer to an application for Let- 80
ters Patent for same intended to be filed si-
multaneously herewith.

E E, Figs. 1, 2, and 3, are boxes for the driv-
ing-quill.

F, Figs. 1, 2, 3, and 4, is the driving-quill 85
which carries the spindle.

G, Figs. 1 and 2, is the balance-wheel.

H, Figs. 1, 2, and 3, is one of the feed-gears,
and is held by friction-clutch H².

H', Figs. 1 and 3, is the gear which drives 90
the gear H.

The friction-clutch H² is mounted on one end
of the feed-shaft T, whose gear H is held be-
tween two disks or plates, h h, which should
be made of some material that will not cut or 95
wear metal to any extent.

H³ is a stationary collar splined to the feed-
shaft T, between its outer bearing, E, and the

gear H, and H' is a movable collar splined to this same shaft on the other side of the gear H. This last-named collar has a tubular hub, h', within which is a spiral spring, h², encircling 5 the end of the shaft T. This spring has bearing at its inner end against a shoulder, h³, at the base of the hub h', and has bearing at its outer end against an adjusting-nut, V. This nut screws upon the shaft T, and its base is of a diameter to nicely fit the bore of the hub h'. By means of this nut the spring is compressed against the shoulder h³ and the collar H', together with the adjoining disk or plate h, at any desired pressure. This pressure is to be regulated 10 by the nut V, and the gear H is thereby held more or less firmly between the disks or plates h h to revolve with the shaft T. If the resistance to the quill F and spindle N be less than the friction or pressure applied by the disks or 15 plates h h to the gear H, they will then work readily through the medium of the gears H and H'; but if the resistance equals or exceeds said friction or pressure the gear H will slip more or less between the disks h h, and independent, 20 to that extent, of its shaft.

I, Fig. 1, is the engine-frame which holds the cylinder and crank.

KKK, Figs. 1 and 2, is a cap of engine-frame, preferably made in a single piece. It also 30 forms a part of the bearings for the crank-shaft.

L, Figs. 1 and 2, is a bevel-gear, which is on crank-shaft, and which drives the gear, L', Figs. 1, 2, and 3, the said bevel-gear L' being on the quill which drives the drill.

M, Figs. 1, 2, and 5, is the plate carrying the trunnion f, Fig. 5, to which one side of the spindle-frame is attached and on which it 35 swivels. The other trunnion is formed by the end of the engine-box, as shown by the dotted line M', Fig. 1, at the opening indicated by X, Fig. 5.

N, Figs. 1, 2, 3, and 4, is the screw-spindle which carries the drill.

O O, Figs. 2 and 3, are friction-plates carrying friction balls or rollers.

P is the guard that holds the friction-balls in place.

Q, Fig. 1, is a hand-wheel with extended hub fastened to a box (which is preferably 50 placed for convenience) on the lower stretcher of the standards. It is threaded inside, and carries a hollow screw, R, with a rod, m'. Their function is to lower the machine when it is desired to remove the drill-rods from the hole being bored, and after the rods have been 55 replaced in the hole to raise again the machine to its proper place for working the rods.

S, Figs. 2, 3, and 4, is the nut-gear threaded to fit the spindle, and which feeds it forward 60 and draws it back, and S' is the gear on feed-shaft T, which drives the nut-gear S.

U is a latch, which holds the feed-shaft in position while the drill is fed forward. The latch is then as shown in Fig. 3. When the 65 drill is to be drawn back, the latch is raised up and the shaft slipped back and the gears H

and H' disengaged and the collar t brought on the other side of the latch.

U is a spiral spring holding in place the latch U.

W, Fig. 3, is a stop-lever mounted on a bracket, W', by a bolt, a. There is a pin, b, Fig. 3, in the nut-gear S, which, when the stop-lever is thrown into position, comes into contact with the lever and prevents the nut-gear from revolving and holds it, but is not so rigid but what if any obstacle is encountered it will yield sufficiently to allow the nut-gear to revolve with the spindle. In drilling, this lever is thrown back out of position; but when it is 75 desired to draw up the drill, the feed-shaft T is thrown back until H and H' are out of gear, the lever is thrown forward, and the nut-gear, being held from revolving while the spindle is being revolved by its driving-gear, the spindle is rapidly drawn up.

c, Fig. 1, is a shoe held by bolts c'. The heads of these bolts c', when screwed up, pinch the plate e and prevent its turning. These bolts pass through the shoe c and hold it in 90 place, even when they and the set-screw are loosened.

l, Fig. 1, is a set-screw, whose object is to force the shoe c against the plate e.

e, Figs. 1, 2, 4, and 5, is a plate turned concentric with the trunnion f, and n is a cap for same.

In mounting the machine on standards, I use a number of special clamps, C' C² C³ C⁴, Figs. 1, 2, and 5. Instead of these, there could be used 100 clamps similar to those I use on the braces, (and for which I intend to apply for Letters Patent simultaneously herewith,) but for obvious reasons it is desirable to have a swing-bolt.

g, Figs. 1, 2, and 5, shows the bolt, and g' the slot in which the bolt swings on the pin g'.

i is the link (secured at each end by a pin) which holds the other end of the clamp c. In mounting the machine I prefer to use four of these clamps, as follows: C' is attached to the engine-frame and top head, one-half of the clamp being cast as a part of the frame and head. Parts of C² and C³ are cast to the bottom head of the steam-cylinder as a part thereof, and extending across (at either end of the arm k) from one standard to the other, thereby making a very stiff support for the machine. Part of C⁴ (clearly shown in Fig. 5) is cast as 115 a part of the plate M and trunnion f, on which one side of the spindle-frame is swung.

o, Figs. 1 and 2, is crank-shaft.

d d d are set-screws to hold the stretchers B to the standards in position.

r r r r are screws for adjusting and holding the standards.

p p p is the spindle-frame, preferably in one piece and forming both the plates e and s, which are turned concentric.

In the practical working of the drill I place 130 one of the brace-clamps D so that the plate M will come into contact with it on the standard.

when the drill is at work, and the lower brace-clamp D so that the plate M shall rest against it when the machine is lowered sufficiently to be out of the way of the drill-rods when it is desired to remove them from the hole being bored. By this arrangement there is no difficulty in always having the machine in its exactly proper position relatively to the hole. It is manifest that any suitable collars could be used on the standards for this same purpose; but the brace-clamps, being there, can be advantageously utilized for the purpose.

In this machine I attach the drill-rods directly to the end of the screw-threaded driving-spindle N, instead of, as heretofore in deep-drilling machines, having the drill-rod pass through the spindle, and I thereby avoid the use of clutches and weight and expense, large journals on the driving-quill, and accompanying friction. To swivel the drill to the desired angle, it is only necessary to loosen the nuts upon the bolts c' and the set-screw l, thereby freeing the plate e from the friction-shoe e. When the drill is adjusted, the set-screw is tightened and the shoe forced against the plate e, and the bolts c' are tightened. The bevel-gears L and L' are so arranged that in swiveling the drill L remains stationary, while L' turns upon L.

30 What I claim, and desire to secure by Letters Patent, is—

1. In a rock-boring machine, the combination, with the parallel standards A A and the connecting-braces B B, of the boring mechanism, and the driving mechanism mounted upon and between said standards by means of two-part clamps C' C' C' C', each having one part made solid with those to be mounted and the other part hinged thereto, substantially as and for the purposes set forth.

2. In a rock-boring machine, the combination of the parallel standards A A, the brace-bars B, adjustable thereon, the brace-bar k, equal in length to the bars B and supporting the driving-cylinder, the clamp C', provided with the link i, swinging bolt g and pin g', and the clamps C', C', and C', all constructed and arranged substantially as described.

3. In a rock-boring machine, the combination, with the parallel standards, the cylinder-supporting frame and clamp C', of the spindle-frame p, the plates e and s, secured thereto, the trunnions of said frame, the binding-plate e, binding bolt and nut c', and set-screw l, all constructed and arranged substantially as described.

4. In a rock-boring machine, the combination of the single-cylinder engine, the crank-shaft, piston, and piston-rod, and the bevel-gear L on the crank-shaft, with the boring mechanism, the clamp C', the spindle-frame p, plates e c, bolt and nut c', and set-screw l, all constructed and arranged substantially as described.

65 5. In a rock-boring machine, the combination, with the parallel standards A A and the

connecting-braces B B and k, of the boring mechanism, the single-cylinder engine, the adjustable clamps C' C' C' C', for mounting said parts, and the hand-wheel Q, its hollow screw R, and center rod, m', arranged between the bottom brace, B, and the brace k, for adjusting the machine up and down, substantially as described.

6. In a rock-boring machine, the combination, with the parallel standards A A, the braces B B, and the driving mechanism mounted upon and between said standards, of the swiveled spindle-frame p, carrying the boxes E E, the driving-quill F, journaled in said boxes, 80 and the screw-spindle N, passing through said quill and adapted to carry the drill-rod on one end, substantially as and for the purposes set forth.

7. In a rock-boring machine, the combination, with the single-cylinder engine, the piston, piston-rod, crank-shaft, and bevel-gear L on said shaft, of the spindle-frame p, the driving-quill F, journaled in said frame, the bevel-gear L', friction-plates O O, intermediate friction balls and gnard, P, arranged on said quill, and the screw-spindle N, passing through said quill and carrying the drill-rod on one end, substantially as described.

8. In a rock-boring machine, the combination, with the parallel standards A A and the driving mechanism mounted upon and between the same, of the spindle-frame p, carrying the boxes E E, the driving-quill F, journaled in said boxes and carrying the gear L', 100 and the inclosed screw-spindle N, the parallel feed-shaft T, journaled in said spindle-frame, and the intermediate shaft-gearing, S S' and H H', substantially as described.

9. In a rock-boring machine, the combination, with the supporting-frame and the driving mechanism, of the spindle-frame p, the driving-quill F, mounted in said frame p, the screw-spindle N within said quill, the parallel feed-shaft T, provided with the collar t, the 110 intermediate gearing, S S' and H H', and the spring-controlled latch U, pivoted in said spindle-frame and operating in connection with the collar t, substantially as and for the purposes set forth.

10. In a rock-boring machine, the combination, with the supporting-frame and the driving mechanism, of the spindle-frame p, the driving-quill F, mounted in said frame p, the screw-spindle N, within said quill, the parallel feed-shaft T, the intermediate gearing, S S' and H H', and the adjustable friction-clutch H' on the outer end of said shaft, substantially as and for the purposes set forth.

11. In a rock-boring machine, the combination, with the supporting-frame and the driving mechanism, of the spindle-frame p, the driving-quill F, mounted in said frame p, the screw-spindle N, within said quill, the parallel feed-shaft T, the intermediate gearing, S S' and H H', and the adjustable friction-clutch H' on the end of said shaft, comprising a

spiral spring, and a screw-nut for adjusting and regulating the pressure of said spring, substantially as described.

12. In a rock-boring machine, the combination, with the driving-quill F and its drill-spindle N and gear H', of a feed-shaft, T, a loose gear, H, mounted upon said shaft, a fixed collar on one side and a movable collar on the other side of said gear, and a spring for pressing the latter against said gear, substantially as described.

13. In a rock-boring machine, the combination, with the drill-spindle and its driving-gear, of a feed-shaft, a loose gear mounted upon said shaft between two disks or plates, a fixed and a loose collar embracing said disks or plates, a spiral spring arranged within said movable collar, and an adjusting screw-nut,

all mounted upon said shaft, substantially as and for the purposes set forth. 20

14. In a rock-boring machine, the combination, with the supporting-frame and the driving mechanism, of the spindle-frame p, the feed-shaft T, mounted therein and carrying the gears H and S', the driving-quill F, carrying the gear H', the inclosed screw-spindle N, carrying the nut-gear S, provided with pin b, and the bracket W', carrying the pivoted detent-lever W, substantially as and for the purposes set forth. 25

In testimony whereof I affix my signature in presence of two witnesses.
